UNITED STATES PATENT OFFICE.

MARTIN W. POND AND HENRY E. MUSSEY, OF ELYRIA, OHIO.

BREAST-STRAP SHIELD FOR HARNESS.

Specification forming part of Letters Patent No. 44,113, dated September 6, 1864.

To all whom it may concern:

Be it known that we, MARTIN W. POND and HENRY E. MUSSEY, of Elyria, in the county of Lorain and State of Ohio, have invented a new and useful Improvement in Metallic Shields for Breast-Straps; and we do hereby declare that the following is a full, clear, and exact description thereof, reference being had to the accompanying drawings, and to the letters of reference marked thereon, in which—

Figure 1 is a section taken in line $x x$. Fig. 2 is an inverted plane.

The nature of our invention consists in providing the breast-strap of a harness with a metallic shield, which is so constructed that the neck-yoke ring is secure in its seat, and is thereby prevented from any lateral vibration, as will be more fully set forth in the following specification.

To enable others skilled in the arts to make and use our invention, we will proceed to describe its construction and operation.

A represents a curved metallic plate, on the ends of which loops $a a$ are formed, through which the breast-strap passes. Said plate is provided with flanges $b b$, which are formed on its edges, and serve to keep the strap in place. The lower surface of said plate is smooth.

$c c$ are projecting horns, which spring from the upper surface of said plate and are positioned on opposite sides of it. Their upper ends are curved so as to form a hook on each one. Said hooks are curved in opposite directions, and lock past each other in such a manner that when the ring is placed in a diagonal position it will pass between the horns

and readily fall into its seat at their base, in which case it assumes a transverse position, and it is impossible for it to become accidentally removed. The base $d d$ of the horns $c c$ extend transversely and parallel across the upper surface of the plate, and form the seat f . They are somewhat elevated, and the groove formed by them is just wide enough to admit the ring, and is curved so as to just fill the curve of the ring. Thus, when the ring is secured in position, it is securely clamped or held firmly, so that there is no (or not much) vibration or side motion. This is an important result, as when the shield is applied to practice the vibration of the pole is at times very great, and unless the ring can be made in effect a part of the shield, so as to force said shield along on the strap by its leverage, it is sure to bend and cramp so as to almost destroy the effect of the shield. By obviating this we overcome all the objections to my patent of 1864, wherein I obtained a claim on the use of the horns $c c$.

What we claim as new, and desire to secure by Letters Patent, is—

The curved metallic shield, having curved metallic horns, as described, in combination with the projections or base of horns forming the clamping-seat f of the shield, the whole being constructed in the manner and for the purpose described.

M. W. POND, [L. S.]
HENRY E. MUSSEY. [L. S.]
